3 Claims

ABSTRACT OF THE DISCLOSURE

A handle device for mounting on contoured surfaces, the handle device comprising a grip having mounting brackets rotatably mounted on each end of the grip for rotation about a transverse axis whereby the handle device may be conveniently mounted on any convexly contoured surface.

Oftentimes, in the repair of old model refrigerators, freezers, ranges and the like, a replacement handle must be provided to manipulate the door of the unit. Typically, the repairman cannot repair the handle, which also serves as a latch, and must supply a new handle which may be obsolete. Therefore provision must be made for a replacement handle and latch mechanism as required.

In my co-pending application entitled Magnetic Latch, filed Dec. 15, 1966, under Ser. No. 602,037, now U.S. Pat. No. 3,403,933 I disclosed and claimed a magnetic latch as a replacement latch for refrigerators, freezers and the like. The replacement magnetic latch fits any and all units and obviates the need for the repairman to stock latches for various types of obsolete units. However, I have found in utilizing the magnetic latch disclosed and claimed in the above entitled application, that a handle device must also be provided to replace combination latches and handles.

Handles presently on the market, which could serve as replacement handles, typically do not fit all contoured surfaces. Further, a handle which would fit most contoured surfaces, may not fit the decor of the unit on which the handle was to be attached. Therefore a wide variety of replacement handles must be stocked by the repairman. Additionally, the replacement handle must direct the forces exerted on the handle to open or close the door to the most advantageous position relative to the location of the replacement latch.

With these comments in mind, it is to the elimination of these and other disadvantages to which the present invention is directed along with the inclusion therein of other novel and desirable features.

An object of my invention is the provision of a new and improved handle device of simple and inexpensive construction and operation for mounting on contoured surfaces.

Another object of my invention is the provision of a handle device for mounting on any and all convexly contoured surfaces including surfaces which join at substantially 90°.

Still another object of my invention is the provision of a handle device for mounting on contoured surfaces, which handle device directs the opening or closing forces to the most advantageous point relative to the location of a replacement latching mechanism on the door.

A further object of my invention is the provision of a handle device for mounting on contoured surfaces which may be quickly and efficiently attached to a contoured surface by a person of minimum skill and manual dexterity.

These and other objects and advantages of my invention will more fully appear from the following description made in connection with the accompanying drawings

2

wherein like reference characters refer to the same or similar parts throughout the several views, and in which:

FIG. 1 is a perspective view of the handle device of my invention;

FIG. 2 is a perspective view of the handle device of my invention shown on a refrigerator which includes a magnetic latch assembly attached thereto;

FIG. 3 is a perspective view showing an alternate attachment of my handle device to a contoured surface;

FIG. 4 is a perspective view showing another alternate attachment of my handle device to a contoured surface;

FIG. 5 is an enlarged bottom, plan view taken along the lines 5—5 of FIG. 3; and

FIG. 6 is an enlarged partial sectional view taken along the lines 6—6 of FIG. 3.

One form of the present invention is shown in the drawings and is described herein.

The handle device of my invention, as shown in FIG. 1 generally indicated by numeral 10, includes a grip. Grip

20 11 includes an elongate hand receiving portion 12 and an angulated bracket mounting portion 13 integral therewith. At the other end of elongate hand receiving portion 12, an angulated elongate bracket mounting portion 14 is integral with grip 11. Bracket mounting portion 13 includes recess 15 and elongate bracket mounting portion 14 includes recess 16, on each side thereof. Typically, grip 11 is constructed of die cast zinc and is chrome plated.

A pair of mounting brackets 17 are shown attached to bracket mounting portions 13 and 14 respectively. The pair of mounting brackets 17 includes a contoured surface engaging plate 19. Saddle 18 is defined by flanges 20 which are in opposed parallel relation and project outwardly from surface engaging plate 19. A reinforcing gusset 21 is positioned between flanges 20 and surface engaging plate 19. Mounting screw or bolt receiving openings 22 are positioned in surface engaging plate 19 to receive screws therein to attach mounting bracket 17 to a contoured surface. Typically, brackets 17 are contoured of die cast zinc and are chrome plated.

Bracket mounting portion 14 has opening 23 therein, transversely of the elongate grip, which passes through recess portion 16. Bracket mounting portion 13 has a corresponding opening not shown herein. The recesses of the respective bracket mounting portions 13 and 14 are sandwiched between flanges 20 of the pair of mounting brackets 17. Openings 24 in flanges 20 receive a roll or tension pin 20a therein rotatably mounting the bracket mounting portions 13 and 14 to the brackets 17. The tension pin is commercially available and is inserted through flange opening 24 and through opening 23 in the recess of the bracket mounting portion.

Referring to FIG. 2, the handle device 10 is shown mounted on a refrigerator 25. A magnetic latch, indicated in general by numeral 26, is shown mounted on refrigerator 25. Handle 10 is shown on contoured door 27 with elongate bracket portion 14 positioned around the corner of the door for a mounting in which the respective mounting brackets 17 are substantially at right angles. In this position, elongate hand receiving portion 12 is substantially parallel with the front surface of the door. Since the handle device is moved very close to the outer edge of the refrigerator door, maximum pulling power is generated so that the forces of magnetic latch 26 may readily be overcome.

In FIG. 3, handle device 10 is shown mounted on contoured surface door 27' transverse to the hinge line of the door. It should be noted that bracket mounting portion 14 is away from the hinge line. This orients the hand to pull at a point away from the hinge line thereby maximizing the pulling forces. In FIG. 4, handle

device 10 is shown mounted on door 27", upright and parallel with the hinge line. In this position, the elongate bracket mounting portion 14 is positioned upwardly thereby urging the hand upwardly. In the above manner, the pulling forces can be oriented as desired, depending upon the location of the latching mechanism.

It should be noted, as shown in FIG. 5, that the relation between the bracket mounting portion 13 and the elongate bracket mounting portion 14, as shown by the dimensions X and Y respectively, is approximately 2 to 1. I have found that this is the optimum proportion between the opposed bracket mounting portions to provide a handle which may be utilized on any and all convexly contoured surfaces while providing a functional and decorative handle which is easy to grip and manipulate.

In operation, the handle device 10 of my invention is assembled to a contoured surface by first positioning brackets 17 thereon. Grip 11 is positioned, at each end thereof, in saddles 18; and a "throwaway" pin is inserted into aligned openings 23 and 24, temporarily assembling the grip to the brackets in a manner which allows rotation between the brackets and the grip. This rotation allows the repairman to mate the handle to the contoured surface for efficient and attractive mounting. The elongate bracket mounting portion 14 is positioned in relation to the latching mechanism, or the hinges of a door, whereby optimum force location may be provided. In some instances, it is advantageous to position the elongate hand receiving portion substantially parallel with the contoured surface by placing the bracket which receives the elongate bracket mounting portion at right angles to the other bracket. In other instances, the elongate bracket mounting portion is positioned at the point at which it is desired to urge the hand of the operator to maximize the effectiveness of the latch mechanism.

After the brackets have been positioned on the door or contoured surface, the "throwaway" pins are removed, releasing the grip. Screws are threaded into the contoured surface through openings 22, attaching the brackets to the surface. It should be noted that a screw receiving opening 22 is positioned under saddle 18 of bracket 17. The grip is then repositioned in the saddles, and roll pin 20a is inserted through aligned openings 23 and 24 thereby mounting grip 12 to the pair of brackets 17. The roll pin is extremely difficult to remove and therefore, since a screw 22a is inserted through the bracket under the saddle, the handle may not be removed.

From the foregoing it will be seen that I have provided a handle device which is extremely flexible in its use and which may be properly mounted on any and all contoured surfaces, including sharply cornered surfaces. Further, the handle device of my invention may be oriented to co-operate with a latching device and replace a handle which was formerly a latching device and handle combination. Also, my handle device may be oriented relative to a replacement latch to prevent distortion of the door which would otherwise be caused by improper or "makeshift" handle installation. The handle device of my invention may be quickly and efficiently assembled to a contoured surface following the above steps such that an accurate assembly may be obtained by a person of minimum skill.

It will, of course, be understood that various changes

may be made in the form, details, arrangement and proportions of the various parts without departing from the scope of my invention.

What I claim is:

1. A handle device for mounting on appliance doors comprising:

a pair of separate mounting brackets each having an elongated, door engaging plate with fastener receiving apertures therein and handle grip engaging means comprising a pair of parallel, spaced apart flanges extending at right angles to said plate, said flanges being located inwardly from the opposite ends of said plate and defining a saddle therebetween;

a handle grip having an elongated hand receiving portion;

a first, rigid bracket mounting portion at one end of said handle grip and a second, rigid bracket mounting portion of greater length than said first bracket mounting portion at the opposite end of said handle grip, said first and second bracket mounting portions being angularly disposed with respect to said elongated hand receiving portion and rotatably supported within said saddles between said flanges of said mounting brackets on pivot pins extending therethrough for pivotal movement about axes transverse to said elongated hand receiving portion, whereby each of said mounting brackets may be pivoted independently so as to permit the attachment and mating of said handle device on an irregularly contoured door surface or on door surfaces angularly disposed with respect to each other, the greater length of said second bracket mounting portion supporting said elongated hand receiving portion at an angle with respect to the surface of said door to provide an enlarged gripping space between said hand receiving portion and the door surface.

2. A handle device as defined in claim 1 wherein: at least one of said apertures is located between said flanges at the base of said saddle of each of said mounting brackets so as to be covered by the respective one of said bracket mounting portions when said handle grip is assembled to said brackets, thereby preventing the removal of said handle device after it has been installed on a door.

3. An assembly of the handle device of claim 1 in combination with an appliance door wherein:

said handle device is mounted on said door with said second and longest bracket mounting portion located farthest from the hinge line of said door and closest to the door latch, thereby presenting the largest hand grip opening where the maximum pulling force and leverage will be applied to disengage the door latch and open said door.
